[57] **CLAIM**

The ornamental design for a combined cooler and dispenser for wine, as shown and described.

DESCRIPTION

FIG. 1 is a front perspective view of a combined cooler and dispenser for wine showing my new design;
FIG. 2 is a front elevational view thereof;
FIG. 3 is a right side elevational view thereof;
FIG. 4 is a top plan view thereof;
FIG. 5 is a left side elevational view thereof;
FIG. 6 is a rear elevational view thereof;
FIG. 7 is a bottom plan view thereof; and
FIG. 8 is an enlarged fragmentary side elevational view of the rear portion of the spigot of FIG. 5.
